UNITED STATES PATENT OFFICE.

OWEN HOLMES, OF HUNTINGTON, INDIANA.

AUTOMATIC TRAIN-STOP.

1,315,500.

Specification of Letters Patent.

Patented Sept. 9, 1919.

Application filed December 18, 1916. Serial No. 137,637.

To all whom it may concern:

Be it known that I, OWEN HOLMES, a citizen of the United States, residing at Huntington, in the county of Huntington, State 5 of Indiana, have invented certain new and useful Improvements in Automatic Train- Stops; and I do hereby declare the following to be a full, clear, and exact description of the invention, such as will enable others 10 skilled in the art to which it appertains to make and use the same.

This invention relates to improvements in train stops and particularly to devices for automatically applying the brakes and cutting off the steam of a train when approaching or about to enter a danger zone.

One object of the present invention is to provide a simple and effective device of this character whereby the air brake train pipe 20 will be exhausted to apply the brakes to the train, and at the same time the throttle will be closed to cut off steam from the engine driving cylinders.

Another object is to provide novel means 25 for utilizing the exhausting air from the train pipe to close the throttle valve.

Other objects and advantages will be apparent from the following description when taken in connection with the accompanying drawing.

In the drawings:

Figure 1 is a side elevation of my train stopping mechanism shown in connection with a railway, semaphore signal, and locomotive.

Fig. 2 is an end elevation of the track device.

Fig. 3 is an enlarged top plane view of the engine carried mechanism.

Fig. 4 is a perspective view of the air valves, and connections therewith.

Fig. 5 is a vertical sectional view through one of the air valves.

Fig. 6 is an enlarged elevation partly in 45 section, of the throttle actuating mechanism.

Fig. 7 is a sectional detail of the valves and the pipe 49'.

Referring particularly to the accompanying drawings, 10 represents the mast of a semaphore signal, which includes the pivoted arm 11. A contact 12 is carried by the mast, and a contact 13 by the arm, wires 14 and 15 extending from these contacts respectively, and leading to a motor 16 through 55 a source of electricity 17. On the shaft of

the motor is mounted a pinion 18 which meshes with a segmental pinion 19 carried by one end of a centrally pivoted lever 20, mounted adjacent the rail 21 of the railway. Mounted in suitable guides 22, adjacent the 60 said rail, and movable vertically therein, is a frame 23, which supports on its upper end a rail 24, said rail being disposed above the tread of the rail 21 when the semaphore arm is raised to danger position, and below 65 said rail when the arm is lowered into safety position. It will thus be seen that by the movements of the semaphore arm, the contacts will be engaged and disengaged to complete and break the circuit, whereby the 70 motor is driven or stopped to raise or lower the rail 24.

Pivotedly mounted on the frame 25 of the locomotive 26, is a depending arm 27, the lower end of which is bifurcated, as at 28, 75 and has mounted within said bifurcation, the roller 29, said roller being adapted to engage with the rail 24, when the rail is in raised position to cause the rocking of the arm on its pivot. Also mounted on the engine frame, adjacent the upper end of the arm 27, is a pair of valves 30 and 31. In the former there is disposed an apertured slide 32, while in the latter there is disposed an apertured slide 33. A lever 34 extends 80 across the outer ends of the slides and is pivotally connected thereto, said lever being pivotally mounted at its intermediate portion on the frame of the engine. The outer end of the lever 34 is formed with a 85 downturned bifurcated portion 35 which pivotally receives the upper end of the arm 27, whereby when said arm is rocked on its pivot, by contact with the rail 24, the lever 34 will be correspondingly moved to actuate the slides 32 and 33. The valve 30 is 90 located in the pipe 36 which leads from the train pipe 37 to the engineer's brake valve 38, so that when said valve 30 is opened by the movement of the arm 27, the air in the 100 train pipe will be permitted to exhaust into the atmosphere and cause an emergency application of the brakes.

Within the cab of the engine, and mounted on the inner end of the boiler 39, is a cylinder 40, in which is disposed a piston 41. The stem 42 of this piston is pivotally connected to one arm of a bell crank lever 43 which is pivotally mounted on the throttle lever 44. The other arm of the lever 43 is 110

formed with a longitudinal slot 45 which receives a pin 46 carried by the rod 47 of the pawl 48 of the lever 44. To the inner end of the cylinder 40 there is connected a pipe 49 which extends to and is connected with the valve 31. A pipe 49' extends from the other side of the valve 31 into the pipe 36 and is turned in the direction longitudinally of the pipe to receive air as it is discharged 10 through the valve 31, as shown at 51 in Fig. 6.

It will thus be seen that when the semaphore arm is lowered the rail 24 is disposed below the tread of the rail 21, and the 15 operation of the engine carried mechanism prevented. When the arm of the semaphore is raised to danger position, the circuit will be completed to start the motor and cause the raising of the rail 24 into such position 20 that when the roller 29 strikes it the arm carrying the roller will be rocked on its pivot and cause the actuation of the valves 30 and 31, whereby the train pipe will be exhausted and permit the application of the 25 brakes, and at the same time the escaping air will be passed into the pipe 49' and thence into the cylinder 40, which will drive the piston to the other end of the cylinder and move the throttle lever into such position 30 as to completely cut off the steam. The initial movement of the piston causes a slight rocking of the bell crank lever 43 which raises the pawl from the segment 50,

further movement drawing the throttle lever into the position above-named.

It will thus be seen that while the greater part of the air exhausted from the train pipe through the engineer's valve and the pipe 36 passes to the atmosphere, a sufficient quantity is discharged through the upturned portion of the pipe 49' to enter the cylinder 40 and actuate the piston 41 to move the throttle lever and close the throttle valve, thus cutting off the steam.

What is claimed is:

A train stopping mechanism including a throttle lever and an engineer's brake valve, an air conduit leading from the engineer's valve for exhausting the air from the train pipe of the brake system, a cylinder mounted adjacent the throttle lever, a piston in the cylinder and connected to the lever, an air conduit leading from said cylinder, a valve connected to the first pipe, a valve connected to the second pipe, and a pipe connected to the second valve and extending into and turned longitudinally within the first conduit for receiving air from the second conduit when both of said valves are opened.

In testimony whereof I affix my signature in the presence of two witnesses.

OWEN HOLMES.

Witnesses:

W. S. HOLMES,
RAYMOND HOLMES.
